JULIUS H. RICHARDS, OF TORRINGTON, CONNECTICUT, ASSIGNOR TO ECLIPSE MACHINE COMPANY, OF ELMIRA, NEW YORK, A CORPORATION OF NEW YORK

ENGINE STARTER

Application filed November 1, 1923. Serial No. 672,069.

My invention relates to a starter for starting internal combustion engines or the like and the same pertains more particularly to the drive or transmission located between the prime mover such as an electric motor and a member of the engine to be started such as the fly wheel thereof. The object of my invention is to provide a comparatively simple but efficient and reliable drive of this character, whose advantages in construction and mode of operation will be apparent from the description hereinafter given.

In the drawing Fig. 1 is a sectional elevation of a starting apparatus embodying my invention, illustrating a portion of the starting motor and a portion of the fly wheel of the engine; Fig. 2 a plan view of the barrel of the drive; Fig. 3 a section on the line 3—3 of Fig. 2; Fig. 4 an elevation of a plate of one of the sets of friction plates; Fig. 5 an elevation of a plate of the other set of friction plates; Fig. 6 an elevation of the end plate of the barrel; Fig. 7 an edge view thereof partly in section and Fig. 8 an elevation of the locking rings.

In the present instance I have shown my invention embodied in a drive of the outboard type and also of the direct drive type, although it will be understood that the same is applicable to the inboard type and also to the indirect drive type.

Referring to the embodiment of my invention as herein shown the motor M has an extended armature shaft 1 provided with a screw threaded portion 2 and having its bearing in the outer end of a bracket or casing 9 which is secured to the frame of the motor.

Upon the screw shaft there is threaded what may be termed a combined yielding clutch and actuating member which is here in the form of a friction clutch operatively connected with the driving member or pinion 7 through the medium of the barrel 3. This clutch comprises two sets of alternating disks 5 and 6 having the formation illustrated in

Figs. 4 and 5 according to which the disks or plates 5 are provided peripherally with the extensions 24 and intervening recesses 25, and the plates 6 are provided internally with the grooves 20 and extensions 26. The plates 6 are so constructed and adapted as to be threaded into the screw threads of the screw shaft and to be thereby operatively connected therewith so that upon rotation of the shaft the entire clutch, barrel and driving member or pinion are advanced automatically longitudinally towards the fly wheel, whereupon the pinion 7 meshes with the fly wheel 10 and contacts the stop nut 8 at the end of the screw shaft.

The set of friction plates 5 is interlocked with the barrel 3 by reason of the projection of said extensions 24 through the longitudinal slots 19 of such barrel. These plates 5 are connected with the barrel for positive rotary movement and also for a relative longitudinal movement, the slots 19 being made of sufficient length for that purpose. The clutch plates and the barrel are held in proper assembled position by means of the end ring or plate 11 provided with curved slots 21 through which the tongues 23 of the barrel pass. This ring is locked in place by means of the pair of locking rings 13 having projections 29 adapted to fit in the slots 22 in the barrel.

The barrel 3 is operatively connected with the pinion 7 by the engagement of its serrated outer end 28 with the teeth of the pinion whereby such barrel is connected positively with the pinion for rotary movement and connected for relative longitudinal movement. At the inner ends of the pinion teeth a flange 12 is provided whereby the barrel on its inward movement is capable of moving the pinion longitudinally. This pinion has a central smooth bore which is of such diameter as to slide freely along the tops of the screw threads 2. A comparatively heavy spring 90

4 is interposed between the pinion and the clutch.

Describing a cycle of operation of my engine starter and assuming that the drive is in its normal position adjacent the motor instead of its meshed position as shown in Fig. 1, when the motor is operated and the armature shaft 1 is rotated, the drive assembly is automatically shifted longitudinally to the left into the position shown in Fig. 1 at which time the pinion is in mesh with the fly wheel 10 and against the stop nut 8, whereupon the torque of the motor will be transmitted to the fly wheel. When the engine starts on its own power the drive will be automatically demeshed in the well-known way.

When the armature shaft is rotated the clutch being threaded upon the screw portion thereof will automatically move longitudinally towards the left and shift the drive assembly into meshed position as above stated. Owing to the extended length of the slots 19 the friction clutch will move the distance indicated by the arrows B and against the tension of spring 4 after the longitudinal movement of the pinion has been arrested by the stop nut 8. The clutch plates will thereupon bottom in the slots 19 but by that time, if not before, owing to the strength of the spring 4, the torque transmitted through the clutch will exceed the resistance offered by the fly wheel and the latter will thereby be rotated as described.

In the event of abutting of the pinion teeth and fly wheel teeth end to end the clutch and barrel will continue to advance, compressing the spring 4 whereupon by reason of the resistance thus offered to the longitudinal movement of the clutch, the latter will rotate slightly and thereby slightly rotate the pinion and bring its teeth into register with the fly wheel teeth. The spring 4 being then under compression will snap the pinion into full mesh with the fly wheel.

The spring 4 should at all times be of such size and strength as to cause driving torque through the friction clutch in order to crank the engine without compressing beyond the slot spaces B, the length of which slots and the strength of the spring being varied in order to meet the circumstances. The construction and arrangement of the parts of the drive are such that the engine is cranked before there is any possibility of the barrel closing the clearance space between it and the face of the fly wheel and coming into contact therewith.

I claim:

1. An engine starter drive including a rotatable shaft, a driving member adapted to be moved into engagement with a member of the engine to be started, and a multiple disk friction clutch connected with the driving member for rotating it and operatively connected with the shaft for longitudinal movement

thereof when the shaft is rotated and for rotary movement therewith, said clutch comprising a plurality of cooperating friction plates the driving set of which are independently mounted and actuated.

2. An engine starter drive including a rotatable screw shaft, a driving member adapted to be moved into engagement with a member of the engine to be started, and a multiple disk friction clutch comprising two sets of clutch plates, the first set consisting of a plurality of plates which cooperate with each other which are operatively connected with the driving member for rotating the latter, and the second set consisting of a plurality of plates which are directly threaded upon said shaft and thereby independently mounted and actuated.

3. An engine starter drive including a rotatable shaft, a driving member adapted to be moved into engagement with a member of the engine to be started, and a multiple disk friction clutch connected with the driving member for rotating it and operatively connected with the shaft for longitudinal movement thereof when the shaft is rotated and for rotary movement therewith, said clutch comprising a plurality of cooperating friction plates the driving set of which are independently mounted and actuated, and a spring interposed between the other set of plates and the driving member.

4. An engine starter drive including a rotatable shaft, a driving member adapted to be moved into engagement with a member of the engine to be started, a multiple disk friction clutch comprising two sets of clutch plates which cooperate with each other, one set being the driven plates, and a barrel operatively connecting the driven plates with the driving member, the other set of plates being the driving plates which are independently mounted upon and actuated by such shaft.

5. An engine starter drive including a rotatable shaft, a driving member adapted to be moved into engagement with a member of the engine to be started, a multiple disk friction clutch comprising two sets of clutch plates which cooperate with each other, one set being the driven plates, a barrel operatively connecting the driven plates with the driving member, the other set of plates being the driving plates which are independently mounted upon and actuated by such shaft, and a spring arranged within the barrel and interposed between the driven set of plates and the driving member.

6. An engine starter drive including a rotatable shaft which has a screw threaded portion, a driving member mounted to slide on said shaft longitudinally into engagement with a member of the engine to be started, a combined clutch and actuating member operatively connected with the driving member

and the shaft, and a barrel operatively connected with the driving member and with the clutch and permitting a limiting relative longitudinal movement of the clutch with respect to the driving member, said clutch being of the multiple disk type and including a plurality of driving clutch plates which are independently threaded upon said screw threaded portion of the shaft and thereby 10 independently mounted upon and actuated by such shaft.
